UNITED STATES PATENT OFFICE.

JOHN MARSHALL, OF CORDOVA, ILLINOIS.

IMPROVEMENT IN CORN-SHELLERS.

Specification forming part of Letters Patent No. **145,356**, dated December 9, 1873; application filed March 29, 1873.

To all whom it may concern:

Be it known that I, JOHN MARSHALL, of Cordova, in the county of Rock Island and State of Illinois, have invented a new and useful Improvement in Corn-Sheller, of which the following is a specification:

Figure 1, Sheet 1, is a top view of my improved corn-sheller. Fig. 2, Sheet 1, is a side view of one of the cylinder-ribs. Fig. 3, Sheet 1, is a detail top view of a portion of the concave. Fig. 4, Sheet 1, is a detail cross-section of the same, taken through the line *x x*, Fig. 3. Fig. 5, Sheet 2, is a vertical longitudinal section of the machine, taken through the line *y y*, Fig. 1.

My invention relates to improvements in the construction of the concave and cylinder, as hereinafter described.

The corn to be shelled is placed in the hopper A, from which it is fed to the endless apron or elevator, which consists of a wide belt, B, provided with cross-slats C, and passing around rollers D, pivoted to the frame-work of the machine. From the upper end of the elevator B C D the corn falls into the space between the cylinder and concave, where it is shelled. E is the cylinder, which is cast hollow, and with its shell about half an inch thick. The cylinder revolves in bearings upon the frame-work of the machine. In the shell of the cylinder E are formed a number of pairs of holes to receive the shanks of ribs F. These holes are arranged in four, more or less, rows, longitudinal with the cylinder, and in such a way that the ribs F of one row may be opposite the spaces between the ribs of the adjacent rows. The ribs or teeth are made of steel or wrought-iron, are half-round or half-oval in form, and are provided at their ends with shanks projecting at right angles from their flat sides. The shanks of the ribs F, while hot, are passed through the holes in the shell of the cylinder E, and clinched upon its inner surface. The concave is made of cast-iron, in sections G, with semi-cylindrical ribs upon their inner or concave sides, as shown in Figs. 3 and 4. The sections G are arranged about a quarter or three-eighths of an inch apart, and their edges have oblong or oval notches formed in them, which are so arranged that

the notches of the adjacent edges may alternate with each other.

It will be seen that while the said notches supplement the function of the parallel spaces between the sections in aiding the ready discharge or escape of the shelled corn downward, their form and size are also such as to prevent the cobs taking the same course.

The sections G are made with a strong longitudinal rib upon their outer or convex sides, and their ends are inserted in grooves in the curved side pieces H. The side pieces H are made of cast-iron, and are secured to the concave sections G, to each other, and to the frame-work of the machine by long bolts I. One of the bolts I passes through at the back end of the concave, and the others pass through the spaces between the sections of the concave. The bolts I that pass through the frame of the machine pass through slots in the said frame, so that the position of the concave may be adjusted by simply loosening the heads of said bolts, and moving the concave into the required position. The front end of the concave is regulated by gage-screws J.

As the corn is shelled, the kernels pass through the spaces between the sections of the concave G to the apron K, down which they slide to the spout in the bottom of box L, through which they pass to the elevator M, the discharge-spout N of which delivers them into any desired receiver. The cobs, and possibly a very few of the kernels, will pass over the rear end of the concave G, slide down the apron or guide-board O to the screen P of the shoe Q, and the cobs fall from the rear end of said screen. The kernels pass through the screen P, and slide down the guide-board R of the shoe Q into the box L. As the grain falls into the box L it is exposed to a blast from the fan-blower S, by which the chaff is blown out at the rear end of the machine. The tailings are received in a spout in the rear part of the box L, by which they are conducted to the elevator T, and are delivered by its spout U upon the endless apron B C, to again pass through the machine. The box L is agitated laterally to facilitate the passage of the corn, and the screen-shoe Q is agitated longitudinally to facilitate the escape of the cobs.

The various operating parts of the machine are connected by bands and pulleys, or other suitable gearing, and are driven from any convenient power.

Having thus described my invention, together with such other parts as are necessary to form a complete or working machine, I claim—

1. The concave formed of the sections G, having notches in their edges, and arranged near together, as and for the purpose specified.

2. The ribs F, made flat on the under side, oval on the upper side, and terminating at their ends in tapered shanks, and secured to the hollow metallic cylinder by bending said shanks, as shown and described.

JOHN MARSHALL.
